(21) Appl. No.: **29/146,504**

The ornamental design of a deck plank cover extrusion, as
shown and described.

(22) Filed: **Aug. 13, 2001**

DESCRIPTION

(51) LOC (7) Cl. **25-01**

FIG. 1 is a top perspective view of a deck plank cover
extrusion, showing our new design, with a middle portion
broken away to disclose indefinite length; and,

(52) U.S. Cl. **D25/125**

FIG. 2 is an end view thereof, the opposite end view being
a mirror image.
